UNITED STATES PATENT OFFICE

CHARLES J. MORITZ, OF EFFINGHAM, ILLINOIS

ROAD SCRAPER

Application filed June 7, 1929. Serial No. 369,086.

My invention relates to road scrapers and has to do particularly with road shoulder trimming machines.

The invention represents principally an improvement in the road scraping machine shown in my prior Patent No. 1,672,497.

The principal object of my present invention is to enlarge the scope and utility of my prior machine without in any way interfering with its simplicity and intended means of operation.

Another object is the provision of a machine of this character in which the road scraping blade or mold board is capable of 15 more flexible manipulation.

Another object is the provision of a grading machine particularly adapted for cutting a shoulder at the side of a finished road below the surface thereof or in line with the 20 surface thereof as may be required.

In the machine of my invention the mold board is capable of bodily vertical adjustment, tilting adjustment and angular adjustment, all without the sacrifice of the basic 25 principle of the machine wherein the finished road surface is employed as a guide for the grading operation at the side of the road on the shoulder.

Among the most valuable functions of the 30 machine at present used is the grading of a horizontal shoulder or berm at the side of the road and below the same as is done at the present time in the widening of concrete highways.

Other objects and features of the invention 35 will be apparent from a consideration of the detailed description taken with the accompanying drawings wherein

Fig. 1 is a plan view of the complete ma- 40 chine;

Fig. 2 is a fragmentary elevational view of the mold board and adjustments therefor, the view being shown partially in section to facilitate disclosure;

Fig. 3 is a sectional view showing the parts 45 in slightly different adjustment than in Fig. 2;

Fig. 4 is a perspective view of a bracket member which is employed as a mounting for 50 the mold board;

Fig. 5 is a sectional view taken along the line 5—5 of Fig. 2;

Fig. 6 is a view showing one of the functions peculiar and individual to my present type of scraper, and

Fig. 7 is a modified form of a part of the mold board regulating mechanism.

My scraper makes use of a wheel carriage substantially the same as the prior patent referred to with a side extension therefor and a mold board secured to the side extension and adapted to cut a shoulder or berm at the side of a road employing the finished road surface as a guide. The mold board is adjustable to make possible the procurement 60 of any cutting position required in connection with the intended use of the machine.

Referring now to the drawings the wheel carriage comprises a main frame including longitudinal members 10 and 11 formed of channel irons provided with diagonal bracing 12 and 13 carrying rear wheels 14 and 16 supported upon a suitable axle 17 rigidly attached to the frame. Steerable wheels 18 and 19 are provided at the front of the carriage and are secured on bell cranks 21 and 22 pivoted to a cross axle 23 and having their long arms connected by a suitable tie rod 24. The wheels are steerable through an adjusting chain 26 which is moved by a sprocket 27 controlled by a hand wheel 28, and the chain being trained around a pair of sheaves 29—29 attached to a cross piece 31.

The channel members 10 and 11 have reinforcing members 33 and 34 which may also be of channel iron and extend from an intermediate position slightly behind the front wheels to the rear axle. The channels in these members may be employed for supporting counterweights 36—36 which are secured in position by nuts and bolts 37.

In addition to the portion of the frame previously described, a front cross piece 38 is provided which acts as part of the frame and has another function which will be brought out hereinafter. There are also a pair of cross pieces 39 and 41 which cross pieces are formed of channel iron and extend beyond the frame to act as part of a side 55 100

extension from which the mold board is supported.

As a bracket from which the mold board is supported I employ a member 42 (Fig. 4) having a special shape and provided with a vertical bore 43' in which a tubular upright 43 is slidably disposed, a mold board 44 being secured to the bottom of the tubular upright by a bracket 46 which is riveted to the central portion of the mold board and has a boss 46' extending around the lower portion of the tubular upright and supported thereon by a collar 45 secured by a pin 47.

Any other means for obtaining a rigid connection at this point may be employed, such as welding or the like. The top of the tubular upright has secured thereto a bracket 48, a pin 49 being employed for the purpose, and a hand screw 51 being threaded in the member 48 and having its lower end engaging against a portion 42' of the bracket 42 whereby the tubular upright 43 may be drawn upwardly or permitted to fall by gravity for adjusting the mold board with respect to the scraper frame. This permits the mold board to be adjusted to cut below the road surface, as shown in Fig. 6, this function being of great facility when widening concrete highways as is being done now quite extensively.

While the mold board is supported on the tubular upright 43 and this member held by the bracket 42, the cutting load is not borne entirely by the upright 43 and the bracket 42 but is distributed in a manner which will now be set out. This construction which I am now about to describe is in most respects identical with that described in my co-pending application.

Referring now again to the frame the front transverse member 38 has a side extension 38' and the entire cross piece including the side piece is provided with a plurality of apertures 52—52 for attaching draft bars 53 and 54 thereto, the draft bars being connected by a clevis 56 to which a toe chain or cable (not shown) is secured for connection to a suitable source of power such as a tractor. The arrangement of the draft bars 53 and 54 in this manner permits the line of pull to be regulated in accordance with the slope of the mold board and the operation which is being performed therewith. In any event the pull will be outside the wheels. For connection to the mold board I provide a draft member 57 which is connected at 58 to the front extension 38', the rear end of the draft member 57 being secured by bolts 59 to a bracket 61 which encircles the tubular upright 43 just above the boss 46'. As will be seen this places the pull directly in the place where it is needed and relieves the bracket 42 of pulling strain.

For adjusting the horizontal pitch of the mold board I provide a circle frame 62 hav-

ing downwardly extending arms 62' and having a semi-circular portion provided with apertures 63 through any selected one of which a pin 64 may be placed and extended through an aperture provided in the member 57 and since the boss 46 is journaled on the tubular upright 43 the mold board is free to move in a rotary fashion to obtain an adjustment with the pin 64 in any one of the holes 63. In Fig. 1 the full lines show the mold board in the position in which it would be employed for cutting a horizontal road shoulder even with the road. Fig. 6 shows the position which the mold board would take when cutting below the road surface.

Now as to the manner of securing the bracket 42 to the grader frame this may be done in various ways, but I employ a construction which will permit the angular tilting of the mold board where this seems to be necessary. The bracket 42 is provided with bifurcated portions 42'' which have apertures 66—66 for receiving a bolt 67, this bolt 67 being extended also through apertures in the extensions of the members 39 and 41. Also secured in the same fashion and within the bifurcated portions 42'' is a channel member 68, a screw 69 being threaded in a boss on the bracket 42 and having its lower end extending into connection with the member 68. A hand piece 71 permits the turning of the screw 69 and the tilting of the bracket 42 around the bolt 67 as a pivot and in order to avoid excessive movement of the bracket in either direction arcuate slots 72 are provided in the bracket 42 and a pin or bolt 73 also connected across the transverse members 39 and 41 extend into these slots. The bracket is accordingly permitted movement within the limits of the slot.

As in my prior machine I employ a shoulder wing cutter 74 pivoted to the mold board at 76 and provided with an arm 77 connected by a link 78 to a bell crank 79 pivoted around the tubular upright 43 and adapted for operation by a chain 81 controlled by a hand wheel 82. The details of operation of this hand wheel will not be referred to as they have been pointed out at length in the preceding patent. In order to avoid a direct strain on the pivot pin 76 I secure a bracing member 83 to the wing cutter 74 in the form of a T iron having an extending end 83' adapted to bear against an arcuate bearing member 84 carried by the mold board. It will be seen that full freedom of operation of the wing cutter 74 is permitted about its pivot by this construction, but bracing is accomplished sufficient in value to amount to substantially an integral construction of these two members.

In the operation of the machine it may be used to cut substantially any kind of a path on the side of the finished road employing the road surface as a guide so that no grad-

ing means or checking of newly graded or about to be graded terrain at the side of the road is necessary. If it is required to lower the mold board, for instance, or raise it, this 5 may be done by turning the hand wheel 51.

The mold board may be adjusted to be absolutely horizontal or parallel to the plane of the road, or the hand lever 71 may be operated to tilt it in either direction. When actu-

10 ally used it is obvious that the strain of drawing the mold board through the earth is borne by the draft member 57 and very little or no strain is borne by the side extension or the side mounting bracket 52. The wing cutter

15 74 may be adjusted to various angles by turning the hand wheels 82, and this is done whether the grader is in operation or not.

The arm 83 will take the strain off of the pivot 76 permitting easy adjustment of the 20 wing cutter and avoiding breaking or straining thereof.

In Fig. 7 I show a modified arrangement which will positively prevent the mold board from raising under any circumstances, the 25 weight of the mold board not being depended upon to lower it. In this arrangement I make use of the same general type of casting 142, and the tubular upright 143 is slidable therein as in the main view. The member 148

30 is substantially the same except that the spindle 151 is not threaded therein but is threaded instead into the portion 142' of the bracket 142. Collars 186—186 pinned or otherwise suitably secured to the spindle 151 hold it in 35 fixed rotatable position with respect to the bracket 148. For this reason turning the hand wheel connected to the spindle or screw 151 turns this screw with respect to the bracket 142 and results in raising or lowering 40 of the entire assembly carried by the upright 143.

This same general idea is carried out in connection with the adjusting screw 169 this screw having collars 187 secured thereto 45 above and below the boss on the horizontal portion of the bracket 142. The screw 169 is threaded into a ball 188 which with a bi-part block 189 forms a universal joint connection to the web 168a. Consequently turning the screw 169 in either direction will tilt the bracket 142 and the ball and socket arrangement allows for the changing angle so that no bending action is applied to the adjusting screw.

50 I have described in detail features of my invention as embodied in a form of a machine which I have employed with satisfaction in actual use, but it is obvious that I do not limit myself to these details, the invention being limited only by the scope of the appended claims.

What I claim as new and desire to protect by United States Letters Patent is:

55 1. In a road grader a wheeled frame, a side extension thereof a bracket carried by the

side extension, a mold board suspended from the bracket and adapted to cut a horizontal shoulder entirely beyond the wheel line of the wheeled frame, means operable to obtain bodily vertical adjusting movement of the 70 mold board and means for moving the bracket with respect to the side extension to effect the angular adjustment of the mold board.

2. In a road scraper a wheeled frame 75 adapted to ride on a finished roadway, a bracket having a pivotal connection to the frame at the side thereof, a mold board suspended from said bracket and means for tilting the bracket with respect to the frame to 80 impart an angular adjustment to the mold board.

3. In a road scraper, a wheeled frame adapted to ride on a finished roadway, a lateral extension on said frame, a bracket pivotally secured to the extension and projecting laterally therefrom, a vertical upright slidable in the bracket, a moldboard secured to the upright, adjusting means for controlling the vertical position of the upright in 90 the bracket to adjust the moldboard bodily vertically, and means for adjusting the position of the bracket to impart an angular adjustment to the moldboard.

4. In a road scraper, a wheeled frame 95 adapted to ride on a finished roadway, a lateral extension on said frame, a bracket pivotally secured to the extension and projecting laterally therefrom, a vertical upright slidable in the bracket, a moldboard secured to 100 the upright, adjusting means for controlling the vertical position of the upright in the bracket to adjust the moldboard bodily vertically, means for adjusting the position of the bracket to impart an angular adjustment to 105 the moldboard, a second side extension in the front of the frame, and a draft link between said front extension and upright, whereby the working strain on the adjustable parts of the grader is lessened.

5. In a road scraper, a wheeled frame adapted to ride on a finished roadway, a lateral extension on said frame, a bracket pivotally secured to the extension and projecting laterally therefrom, a vertical upright slidable in the bracket, a moldboard secured to 115 the upright, adjusting means for controlling the vertical position of the upright in the bracket to adjust the moldboard bodily vertically, means for adjusting the position of 120 the bracket to impart an angular adjustment to the moldboard, the frame including longitudinal members formed of channel irons, and counter weights secured in the channel portions thereof on the opposite side to the 125 moldboard.

6. In a road scraper a wheeled main frame, a mold board secured to project at the side thereof to cut a shoulder at the side of the road with the wheels on the finished road sur- 130

- face, a wing cutter pivoted to the outer end of the mold board, cutter adjusting means on the frame and extending to the wing cutter, a bracing arm secured to the wing cutter and 5 projecting therefrom toward the mold board, and bearing means on to the mold board against which the projecting portion of the arm bears whereby cutting strain on the pivot and adjusting parts is lessened.
- 10 7. In a road scraper a wheeled frame having longitudinal members and front, intermediate and rear transverse members, a pair of channel members serving as portions of the frame constituting intermediate members, 15 and projecting in parallel relation from the side of the frame beyond the wheels, a bracket disposed between the projecting end channel members, an upright slidable in the projecting bracket, a mold board disposed at the 20 bottom of the upright and means for controlling the angular position of the bracket with respect to the projecting channel members to change the angular position of the mold board.
- 25 8. In a road scraper a wheel frame having longitudinal members and front, intermediate and rear transverse members, a pair of channel members serving as intermediate trans- 30 verse members and projecting in parallel relation from the side of the frame beyond the wheels, a bracket disposed between the projecting ends of the channel members and pivotally secured thereto, a filler block below the bracket and secured to the 35 channel members, a mold board supported from the free end of the bracket, and screw means threaded in the bracket and engaging the filler block whereby the angular position of the bracket and mold board with respect 40 to the frame may be controlled.
9. In a road scraper a wheel frame having longitudinal members and front intermediate and rear transverse members, a pair of channel members serving as intermediate trans- 45 verse frame members and projecting in parallel relation from the side of the frame beyond the wheels, a bracket disposed between the projecting ends of the channel members and pivotally secured thereto, a filler block be- 50 low the bracket and secured to the channel members, a vertical upright member slidably supported in the bracket, a mold board secured at the bottom of the upright, screw means disposed at the top of the upright and 55 communicating with the bracket for controlling the vertical position of the upright with respect to the bracket for regulating the height of the mold board, and adjusting means interconnecting the bracket and filler 60 block for moving the bracket about its pivot for controlling the angularity of the mold board.
10. A scraper as described in claim 9 wherein the front transverse member is pro- 65 vided with an extension co-extensive with the
- position of the upright, and a draft bar disposed between the front extension and the upright whereby a direct pull on the mold board may be obtained and the working strain removed from the adjusting parts. 70
11. A road scraper as set forth in claim 9 wherein the front transverse member is provided with an extension, a draft bar disposed between the extension and mold board supporting an upright, a circle frame having a connection to the mold board and an arcuate portion in communication with the draft bar, and means for supporting the arcuate portion in any selected position with respect to the draft bar whereby the cutting angle of the mold board may be controlled. 75
- In witness whereof, I hereunto subscribe my name this eleventh day of May, 1929.
